DESIGN FOR AN ATOMIZER TOP

Fred R. Hoch, Norton, Mass., assignor to T. J. Holmes Co. Inc., Charlton, Mass., a corporation of Massachusetts

Application August 26, 1941, Serial No. 103,014

Term of patent 7 years

To all whom it may concern:

Be it known that I, Fred R. Hoch, a citizen of the United States, residing at Norton, in the county of Bristol and Commonwealth of Massachusetts, have invented a new, original, and ornamental Design for an Atomizer Top, of which the following is a specification, reference being had to the accompanying drawing, forming a part thereof, in which:

Figure 1 is a side elevational view of an atomizer top, showing my new design;

Figure 2 is a top plan view thereof; and
Figure 3 is a front elevational view thereof.

I claim:

The ornamental design for an atomizer top, substantially as shown.

FRED R. HOCH.
